CALCULATING MACHINE

Birney Dysart, Cincinnati, Ohio; Eva Perin Dysart, executrix of said Birney Dysart, deceased, assignor to Eva Perin Dysart, West Hartford, Conn.

Application January 5, 1925, Serial No. 565

65 Claims. (Cl. 235—60)

This invention relates to calculating machines. A general object of the invention is to provide a calculating machine equipped with mechanism operable effectively to accumulate numbers both additively and subtractively and to represent the true algebraic sum thereof at all times notwithstanding the said sum may alternately be of a positive or a negative character.

Another object is to provide a calculating machine of the character aforesaid and having recording means whereby a printed record of the numbers will be made as an incident to the accumulation thereof; and having designating means whereby the record of numbers accumulated additively will be differentiated from that of numbers accumulated subtractively.

Another object of the invention is to provide a calculating machine equipped with calculating devices having a positive zero position and a negative zero position and operable effectively to accumulate numbers both additively and subtractively and to represent the true algebraic sum thereof at all times notwithstanding said sum may alternately be of a positive or a negative character; and having clearing means whereby elements of the calculating devices may be set in either of their zero positions; and having locking means preventing the setting of the elements of the calculating devices in a clear position of a character other than that of the sum then represented thereby.

Another object is to provide calculating machines of the character described with recording means whereby the sum represented by the calculating devices may be printed as an incident to the setting of said devices in their zero positions; designating means whereby the character of the sums printed whether positive or negative may be visibly indicated, and means for printing clear signals to indicate a clear condition of the calculating devices and also to indicate the character of the sum last represented in the calculating devices, i. e., whether positive or negative.

Another object of the invention is to embody in a calculating machine mechanism for cooperating with the calculating devices thereof, whereby when the calculating devices are operated in a reverse direction in the performance of examples of subtraction a correct negative total will be obtained by the automatic transfer of a unit into units denominational order.

Another object of the invention is to provide mechanism for cooperation with the calculating devices to introduce into the units denominational order the unit necessary to obtain a correct nega-

tive total, automatically and as an incident to the operation of the machine to obtain the negative total, and at the same time locking the clearing mechanism against operation until a lock control device is set.

Another object of the invention is to provide equipment in the machine for preventing the operation of the total key devices when there is a negative total in the machine; in order to signify the fact of the presence of the negative total and the fact that operation of the subtraction key is necessary before the machine may be operated in clearing operations.

Other objects will appear from the following description, reference being made to the accompanying drawings, in which—

Fig. 1 is a side elevation of a machine containing the present invention, certain of the parts being broken away.

Fig. 2 is a rear end elevation.

Fig. 3 is a plan view of the calculating mechanism, many of the parts being omitted to clarify the illustration of the present invention.

Fig. 4 is a side elevation of the mechanism shown in Fig. 3, showing one of the calculating pinions set to represent the digit 8.

Fig. 5 is a view similar to Fig. 4 showing the positions of the calculating pinions after 9 has been subtracted from 8 to obtain a negative total.

Fig. 6 is a detail view showing the position of the total key locking device when the machine is operative for straight addition.

Fig. 7 is a similar view showing the position of the total key locking device when the machine is operative for subtraction.

Fig. 8 is a view showing the position of said parts after the machine has been operated in an example of subtraction.

Fig. 9 is a view showing the position of said parts after the machine has been operated an additional stroke preparatory to a printing or clearing operation.

Fig. 10 illustrates an example of work performed by the machine.

Fig. 11 illustrates the devices for restoring to normal position parts of the transfer mechanism.

Fig. 12 is a view showing the mechanism for stopping the counting pinions in clear position when the machine is operated in clearing or total printing operations.

Fig. 13 is a sectional view of the machine showing the character printing mechanism and accumulator control mechanism in normal position.

of the total key and mechanism controlled thereby in their operated positions.

Fig. 15 is a view of the character printing mechanism with the subtraction key depressed.

Fig. 16 (Sheet 1) is a rear elevation of an alternative form of a part of the invention for introducing an additional unit subtractively into units adding pinion.

Fig. 17 is a view looking toward the right hand side of Fig. 16.

Fig. 18 is a detail view showing the parts 152 and 153 from the front of the machine.

Fig. 19 is a sectional view on the line 19—19 of Fig. 16 showing the means for tripping the transfer actuator latch for units counting pinion.

Fig. 20 is a vertical longitudinal sectional view of a part of the machine showing in side elevation the usual Dalton lock device for cooperating with the total key link to require a blank stroke before the clearing operation may be performed.

Fig. 21 is a rear elevation of the total key lock device out of position to block the total key link so that the machine may be operated in a clearing operation.

Fig. 22 is a rear elevation of the total key lock device in position to block the total key link so that the machine cannot be operated in a clearing operation until after a blank stroke.

The usual method for taking care of the "one" in adding and direct subtracting machines is to provide for the introduction of one unit subtractively into units adding pinion as an incident to the operation of the subtraction key to change the machine from adding to subtracting and also by likewise introducing one, this time additively, when the subtraction key is released and the machine thereby restored to condition for accumulating numbers additively. The introduction of the one is not consummated until a subsequent operation of the machine, the movement of the subtraction key merely setting a part, just as though the units digit key had been operated. The following operation of the machine introduces the one into the adding pinion.

As a result, the adding pinions do not represent at all times the true algebraic sum or total of the items that have been added. It consequently becomes necessary to safeguard the machine against the possibility of taking a total under such conditions.

As a result of the present invention, the automatic one is introduced when, and only when, it is necessary in order that the adding pinions may at all times represent the true algebraic sum of the items that have been added. The introduction of the unit is accomplished as an incident to the operation of the machine in which a change from positive to negative or from negative to positive occurs. It, therefore, greatly simplifies the operation of machine and each time saves an unnecessary handle stroke. It eliminates the necessity for safety locks the adding wheels being at all times in proper condition to have a total taken and requiring no more than the usual "clearing" stroke as is customary in these machines.

This invention is capable of application to machines having more than one set of adding pinions. In such applications the advantage resulting from the automatic introduction of the one is vastly increased, as the character of the safeguards and locks that would otherwise be necessary in such machines assumes bewildering proportions.

The machine in which I have shown the pres-

ent invention embodied is a Dalton adding machine containing also essential parts of the invention of Elmer H. Dreher disclosed in application Serial No. 686,036, filed January 14, 1924. Said machine comprises a laterally movable differential carriage 1 into which numbers are set up by the operation of the numeral key levers 2. Racks 3 are limited in their forward movements by the differential stops in the carriage 1 and numbers may be printed upon paper passing around a paper roll 4 in the usual manner. The racks and the type carriers 5 are pivotally supported upon a shaft 6. The type carriers have rearwardly extended arms 7 and are normally held in their idle positions by a rod 8 which is moved downwardly and forwardly when it is desired to operate the type carriers. The movement of the rod 8 is controlled by the forward and back turning movements of a shaft 9 in a well known manner. The machine contains the usual total key 10, and a link 11 operatively connected with the total key device and moving rearwardly at each operation thereof. It is a familiar fact that the Dalton adding machine employs a lock device 14229 to prevent rearward movement of the link 11 and thereby prevent operation of the total key device until after the blank stroke. This familiar locking device for the total key link of the Dalton adding machine is clearly shown in Figs. 20 to 22, inclusive. When the differential carriage 1 is in its normal or starting position a projection 44062 is bearing against the end of an arm 14232 and holds it to the right relative to the operator at the front of the machine (to the left as seen in rear elevation in Figs. 21 and 22). This arm 14232 is constantly under the tension of a spring 64076 and as soon as the differential carriage 1 moves from its starting position the arm 14232 will follow the projection 44062, thus moving the lock 14229 across the rear end of the total key link 11 by a projection 54078 on said arm 14232 bearing against the edge of the lock 14229. A spring 64077 connects the lock 14229 with the arm 14232. The arm 14232 and the lock device 14229 are both supported on a pivot 34018. On rearward turning movement of the shaft 9 as is well known the carriage 1 is moved to its starting position. A link 14147 is operated by said shaft 9 and has a cam C for engaging the tail of the latch 14230. When the arm 14232 and the lock 14229 move to the position shown in Fig. 22 the latch 14230 immediately snaps over the ear G on the lock 14229 as shown by dotted lines (Fig. 22). Then as the shaft 9 is turned forwardly it causes the cam C on the link 55 14147 to move under the tail of the latch 14230 and to disengage said latch from the ear G. But the lock 14229 will continue to block the total key link since the differential carriage 1 is still out of normal position so that the spring 64077 60 is not held under tension by the projection 44062. As the shaft 9 turns toward its starting position the cam C is moved away from the tail of the latch 14230 and the latch again engages the ear G before the projection 44062 on the differential 65 carriage 1 engages and moves the arm 14232 to stretch the spring 64077. When the shaft 9 reaches its starting position the differential carriage 1 is restored to its starting position and the projection 44062 holds the arm 14232 in the 70 position shown in Fig. 21, thus stretching the spring 64077 but not releasing the total key lock 14229 because said lock is held by the latch 14230, as shown in Fig. 22. On the next operation of the main shaft 9 the differential carriage 1 re- 75

mains in its starting position and when the cam C again disengages the latch 14230 from the ear G the spring 64071, which is now under tension, moves the lock 14229 out of the path of the total 5 key link 11.

The invention of the Dreher application comprises a series of sliding actuators 12 connected with the type carrier arms 7, respectively, by links 13 so that when the type carriers are actuated forwardly by their springs 14 the actuators 12 are moved downwardly. While the specific structure of some of the parts included in the calculating device, as herein shown, differs slightly from the structure of the corresponding 10 parts of the Dreher application, the principle and mode of operation thereof up to the point of cooperation with the present invention remain practically the same. A brief description herein of the mechanism covered by the Dreher application will suffice.

Each sliding actuator 12 supports a rack plate 15 by a pin-in-slot arrangement 16 permitting transfer movements of the rack plates 15 by springs 17. Each rack plate 15 is formed with 20 a rack 18 with which pinions 19 mesh, said pinions being independently rotative on the shaft 20 extending transversely through slots in the rack plates 15. The counting pinions 21 of the calculating device are independently rotative on 25 a shaft 22 which is supported in a swinging frame comprising a pair of arms 23 attached to a rock shaft 24. Each of the rack plates 15 has thereon a rack 25, said racks 25 being in lateral alinement with the rear sides of the pinions 19 which are 30 diametrically opposite from the racks 18 with which the pinions 19 mesh. The shaft 22 is shiftable laterally to move the pinions 21 out of engagement with the pinions 19 into engagement with the racks 25, and vice versa. In work of 35 straight addition the pinions 21 are operated by the racks 25 and in work of subtraction the pinions 21 are operated by the pinions 19. During the forward stroke of the machine the pinions 21 are out of engagement with the racks 25 and the pinions 19, except in the operation of 40 printing a total.

Detents 26 are pivoted on the shaft 20, one for each of the rack plates 15, and have shoulders 27 that are engaged by projections 28 on the rack plates. Springs 29 tend to disengage the shoulders 27 from the projections 28. A series of latch arms 30 are pivoted on a shaft 31 and engage fingers 32 on the detents 26 to hold the detents 26 in position in which the shoulders 27 are engaged by the projections 28 until a transfer operation from a lower to a higher order occurs. Each of the latch arms 30 has an arm 33 extending downwardly and terminating near the pinions 21, the arms 33 having wedge-shaped 55 extremities 34 which are engaged by trip cams 35 attached to the respective pinions 21. In transferring the cams 35 operate the respective arms 33 and release the ends thereof from the fingers 32 permitting the springs 29 to move the detents 26 to the position shown in Fig. 5, in which the shoulders 27 are disengaged from the projections 28 and the extensions 36 on the detents 26 engage the projections 28. This permits the spring 17 to impart a transfer movement to the rack 15 plate 15 introducing an additional unit into the counting pinion 21 that is entrained with the rack plate making the transfer movement. Springs 27 actuate the latch arms 30 to latching 60 positions.

It is with the above described Dreher inven-

tion as it is embodied in a Dalton adding machine that the present invention directly cooperates in the specific form shown. However, it will be understood that the invention may be used in other embodiments and is not restricted to the specific 5 form shown.

A subtraction key lever 38 is pivoted upon a shaft 39 and has a link 40 pivoted to its upper end above the shaft 39 and actuated rearwardly by a spring 41. Depression of the key lever 38 10 moves the link 40 forwardly. When the key lever 38 is depressed it is latched in its depressed position by a projection 42 thereon engaging behind a shoulder 43 on a latch member 44. On a return or backward turning stroke of the shaft 9 the 15 latch is released from the lever 38 by a projection 45 from the arm 46 attached to the shaft 9 engaging a wipe pawl 47 on the latch 44.

A bell crank lever 48 mounted on a pivot 49 has one arm connected with an arm 50^a on the shaft 9 20 by a link 50. A link 51 has its lower end pivoted to the other arm of the bell crank lever 48 and its upper end pivoted to the lower end of a rock arm 52 mounted on a pivot 53, so that a rocking movement is imparted to the rock arm 52 at each 25 complete operation of the shaft 9.

A plate 54 is pivoted on the pivot 53 and has a projection 55 that is engaged by the upper end of the rock arm 52 when the latter is operated, thereby imparting a rocking movement 30 to the plate 54. A plate 56 is supported for vertical sliding movements by the pivot 53 and studs 57. The plate 56 supports for horizontal sliding movements thereon a plate 58, the same being supported for said horizontal sliding movements 35 by studs 59. The plate 58 has pin-in-slot connection 60 with the rear end of the link 40. The plate 58 has a hook 61 adjacent to but normally out of the path of movement of the projection 62 on the plate 54. When the subtraction key 40 lever 38 is depressed the link 40 is moved forwardly, carrying with it the plate 58 which carries the hook 61 into the path of movement of the projection 62 so that on the next operation of the main shaft 9 the unit, including the plates 45 56 and 58, will be raised to its upper adjustment, where it will be retained by a detent 63 engaging in a notch 64 in the plate 56. As the main shaft 9 returns to its starting position and releases the latch 44 from the subtraction key 38, 50 the latter is restored to its raised position, the link 40 is moved rearwardly by the spring 41; and the rearward movement of the link 40 moves the plate 58 rearwardly placing the projection 65 on said plate in the position shown (Fig. 1) which 55 is in the path of movement of the projection 55. The next stroke of the main shaft results in the projection 55 engaging the projection 65 and pushing the plates 56 and 58 downwardly to their lower adjustments. 60

An ear 66 extends inwardly from the plate 56 and terminates in a cam-like edge as shown (Fig. 2). A lever 67 mounted on a pivot 68 has a projection 69 engaging the cam projection 66. A link 70 has one end pivoted to the upper end 65 of the lever 67 and the opposite end supported for sliding movements in the frame plate 71. A spring 72 actuates the link 70 toward the right, when viewed from the rear, holding the projection 69 in contact with the cam ear 66.

A sleeve 73 (Figs. 2 and 3) is mounted for sliding and rocking movements on a stud 74. An arm 75 is rigid with the inner end of the sleeve 73 and another arm 76 is rigid with the outer end 75

of said sleeve. The link 78 has a fork 77 engaging the arm 75.

As a result of these connections depression of the subtraction key 38 followed by operation of the shaft 9 causes the cam ear 66 to rise, permitting the spring 72 to move the link 78 in a direction to move the sleeve 73 and connected arms 75 and 76 outwardly.

In the present invention there is a slide 78, similar to the sliding actuators 12 but disconnected from any type carrier and located adjacent to the sliding actuator 12 in the highest denominational order. This slide 78 is operated by a projection 79 from the sliding actuator 12 in the highest denominational order extending into a hole in the slide 78 (Figs. 3 and 4). The slide 78 has mounted thereon a sliding plate 80 devoid of rack teeth, but otherwise similar to the plates 15 and similarly limited in its movements by a detent 26 which is controlled by the counting pinion 21 in highest denominational order.

A rock shaft 81 has an arm 82 attached thereto and supporting a stud 83 having latching engagement with a notch 84 (Fig. 4) in the arm 75 when the machine is operated in straight addition and until a transfer movement is imparted to the plate 80 in a subtracting operation. Another arm 85 on the shaft 81 has a stud 86 extending in front of the projection 87 from the latch arm 30 in units denominational order. A spring 88 holds the shaft 81 in position in which the stud 83 is in the notch 84 and in which the stud 86 does not interfere with or release the latch 30 controlling the plate 15 in units denominational order.

In the operation of the machine for direct addition and other work, except subtraction, the spring 72 holds the link 78 and thereby the arm 75 in the position shown in Fig. 3 in which a projection 89 on the arm 75 is out of line with the sliding plate 80; but, when the subtraction key 38 is down and the machine is operated, the spring 72 moves the link 78 and thereby the arm 75 to place the projection 89 above and in alignment with the sliding plate 80 so that when a negative transfer operation occurs in the highest denominational order, in the performance of an example of subtraction to obtain a negative total, the sliding plate 80 rocks the arm 75 from the position shown in Fig. 4 to the position shown in Fig. 5. This causes the stud 83 to enter a notch 90 in the arm 75. This movement of the link 78 shifts the entire unit, comprising the sleeve 73 and the arms 75 and 76, from the position shown in Figs. 4 and 6 to the position shown in Figs. 5 and 8.

A cam 90' is between the notches 84 and 90. When the arm 75 is moved from the position shown in Fig. 4 to the position shown in Fig. 5, said cam 90', by pushing the stud 83 downwardly, turns the shaft 81 in a counterclockwise direction, as seen in Fig. 4. This turning of the shaft 81 presses the stud 85 against the projection 87 and releases the latch arm 30 in units denominational order from the finger 32 to permit a transfer movement of the rack plate 15 in units denominational order to introduce the fugitive one. Similarly when the arm 75 is moved from the position shown in Fig. 5 to the position shown in Fig. 4, as hereinafter described, the cam 90' will also rock the shaft 81 and cause a transfer movement of the rack plate 15 in units denominational order to introduce the fugitive one.

75 The movement of the parts from the position

shown in Fig. 4 to the position shown in Fig. 5 effects introduction of the fugitive one when the character of the total is changed from positive to negative; and the movement of the parts from the position shown in Fig. 5 to the position shown in Fig. 4 effects introduction of the fugitive one when the character of the total is changed from negative to positive.

An extension 91 (Fig. 1) from the total key link 11 is pivoted to the forward end of a link 92 10 which has in connection therewith a lower extension 93 and a laterally offset upper extension 94. It is with these two extensions 93 and 94 that the arm 76 cooperates to prevent improper operation of the total key mechanism when the machine is operated in the performance of examples of subtraction. Fig. 6 illustrates the position of the arm 76 with respect to the extensions 93 and 94 when the machine is operable for all work other than subtraction.

Illustrating a simple example of subtraction to obtain a negative total wherein a minus amount is indicated, as when a greater number is subtracted from a lesser, 9 subtracted from 8, for instance: Assume that 8 has been set up in the 25 units pinion 21, said pinion appears as in Fig. 4 with its cam 35 in the position there shown. Next the digit 9 is set up in the differential carriage 1, after which the subtraction key 38 is depressed. Then, the shaft 9 is turned forwardly, 30 as an incident to which the pinions 21 are shifted into engagement with the pinions 19 by mechanism disclosed in the Dreher application, and which is not essential to describe here, it being sufficient for present purposes to assume that 35 such shifting does occur. As the shaft 9 returns to its starting position the pinions 21 mesh with the pinions 19 and in this operation the units pinion 21 is turned nine teeth in a counter-clockwise direction (Fig. 4), causing the cam 35 on 40 units pinion to trip the latch arm 30 in tens denominational order and causing a transfer operation through every higher numerical order, with the result that the arm 75 has rocked from the position shown in Fig. 4 to the position shown in 45 Fig. 5 and the shaft 81 is rocked in opposition to the spring 88 to cause the stud 86 to release the latch 30 controlling the sliding plate 15 in units denominational order, thus advancing the pinion 21 in units denominational order one 50 tooth in a negative transfer operation. It is now clear that the laterally shiftable pinions 21 are rotatable in either of two positions. In one of their lateral positions, the pinions 21 are rotatable by the pinions 19 and, in their other lateral 55 position, said pinions 21 are rotatable by the racks 25. The total key device 10 might now be operated and the link 11 moved to the rear as required for taking a total, except for the fact that the rear end of the link 11 is blocked 60 in the familiar manner and by the familiar device 14229 of the Dalton adding machine so as to require an oscillation of the shaft 9 while the differential carriage 1 is in its idle or starting position. That is to say, this Dalton total key device 65 cannot be operated until after a forward and return movement of the shaft 9 has been made while the differential carriage 1 is in its idle or starting position. It will be understood, of course, that this blank operation has not yet occurred, 70 the last preceding operation above described having been the subtraction of the item causing the negative total, during which operation the differential carriage was out of its idle or starting position.

The operator has not yet received warning from the machine that the total has changed from positive to negative, and in ignorance of such fact now proceeds to place the machine in condition to print a positive total by operating the machine for the usual blank clearing stroke. As is well known, the usual blank clearing stroke comprises rocking the shaft 9 forwardly from its starting position and rearwardly to its starting position. As a result, the pinions 21 are shifted laterally to position to mesh with the racks 25, the unit of which the arm 76 is a part shifts laterally until said arm 76 is in alignment with the extension 94 of the total key link 11, as seen in Fig. 9. This makes it impossible to operate the total key 10 and an attempt to operate the locked total key 10 indicates to the operator the presence of a negative total in the machine. To print this negative total it is necessary to make two operations of the machine—the first operation (with the subtraction key 38 depressed) shifts the arm 76 from the position shown in Fig. 9 to the position shown in Fig. 8, and the second operation while both the total key 10 and the subtraction key lever 38 are in their operated adjustments. On the latter operation the negative total was printed and the machine cleared. On the next forward turning movement of the shaft 9 after release of the key lever 38, the arm 76 shifts from the position shown in Fig. 8 to the position shown in Fig. 9 in which case an extension 95 of the arm 75 is over a projection 96 on the plate 80. As one or more of the plates 15 rise on the next stroke of the machine to add another amount, the corresponding pinion or pinions 21 are rotated in the usual clockwise direction (Fig. 4) to engage the cams 35 on the negative side of the wedge-shaped extremities 34, tripping the latches 30, permitting a transfer movement of all of the plates 15 and the plate 80, causing the projection 96 to restore the unit 73—75—76 to its starting position (Figs. 3, 4 and 6). It is necessary to restore the detents 26 to position to engage the shoulders 27 with the projections 28. A bail 97 is pivoted upon the shaft 31 (Figs. 11 and 12) and is normally held back against a plate 98 by a spring 99.

A lever 100 is pivoted upon the shaft 31 and has a stud 101 adapted to operate the bail 97 by engaging an extension 102 of the bail. The bell crank 100 is operated by a link 103 connecting the same with the plate 54 which, as previously described, is oscillated at each operation of the main shaft 9. Accordingly, the bail 97 will be operated near the end of the forward stroke of the machine, i. e., near the end of the forward turning movement of the shaft 9, effectively to move the detents 26 to place the shoulders 27 in line with the projections 28 and permit the latches 30 to engage behind the fingers 32.

During each clearing or total printing operation it is necessary to lock the latches 30 which support the arms 33 in order to stop the pinions 21 in proper position.

A bail 104 is pivoted upon a shaft 105 and is movable to and from position under the tails of the latches 30 by a spring 106. When the bail is under the tails of the latches 30 said latches cannot be tripped by the cams 35. The rock arm 52 has a stud 107 extending over the forward end of a lever 108, the rear end of which extends under a projection 109 on the bail 104 and normally holding the bail in its rear position to permit tripping of the latches 30. A block mem-

ber 110 is pivotally supported by the shaft 31 and during active adding or other calculating operation of the machine prevents the bail 104 from moving under the tails of the latches 30 so that said latches may be tripped for transfer operations.

A downward extension 111 from the link 92 when it is moved rearwardly by operation of the total key 10 engages a roll 112 on an extension 113 of the block member 110, thereby raising the block member 110 and permitting the spring 106 to move the bail 104 under the tails of the latches 30, thereby locking said latches against being released, with the result that the counting pinions will be stopped in clear position upon a clearing or total printing operation of the machine.

The counting pinions 21 are normally in mesh with the racks 25, but when an item is being listed said pinions are disengaged from said racks before the beginning of the descent of the racks. Such disengagement of the pinions is effected by operation of a cam 113a (Figs. 13 and 14) which, during forward turning movements thereof, engages a roll 114 on one of the arms 23 and thereby swings the arms 23 rearwardly to carry the pinions 21 out of engagement with the racks 25. The cam 113a is operated by a wipe pawl 115 on an arm of the lever 48 and adapted to engage a stud 116 on one of the associated parts of the cam 113a. To print a total represented in the pinions 21 it is necessary to retain the pinions in mesh with the racks 25 during the forward stroke of the machine, which result is obtained by moving the stud 116 out of the path of movement of the wipe pawl 115 so that the shaft 9 may turn forwardly to effect a forward stroke of the machine without disengaging the pinions 21 from the racks 25. The stud 116 is attached to a plate 117 supported on the same pivot 118 that pivotally supports the cam 113a. A cam plate 119 is slidably supported by the cam 113a and normally held in raised position by a spring 120. A cam slot 121 in the plate 119 receives a stud 122 extending from the plate 117. In order to print a positive total contained in the counting pinions 21 the total key 10 is operated, moving the link 92 rearwardly. An operative connection 123 from the link 92 to the shaft 124 imparts rocking movements to said shaft. An arm 125 from the shaft 124 is connected by a link 126 with one arm of a bell crank lever 127, the other arm of which bears upon a stud 128 projecting from the cam plate 119. When the total key 10 is operated and the link 92 is moved rearwardly thereby, the cam plate 119 is pushed downwardly and, by means of the cam slot 121, turns the plate 117 to a position in which the stud 116 is out of the path of movement of the wipe pawl 115. This leaves the pinions 21 in mesh with the racks 25 on the forward turning movement of the shaft 9. As the racks 25 descend during forward turning movement of the shaft 9 the pinions 21 are turned by their respective racks until the cams 35 engage on the upper surfaces of the cooperating latches 34 (Fig. 4). The type carriers 5 are thus properly positioned for printing the total contained in the counting pinions 21.

A total of negative value is printed in a similar manner, except that as the operation is performed with the subtraction key 38 depressed, the counting pinions 21 turn in a clockwise direction (Fig. 4) during descent of the actuator causing the cams 35 to abut against the lower surfaces of the latches 34.

The type carrier 5, which is to the right of the 75

numeral type carrier in the lowest denominational order, carries the designating character type including preferably a minus sign. The designating character type carrier is stopped in proper printing positions by a heel 129 contacting with one or the other of the stop arms 130, 131 and 132 which are pivoted upon a shaft 133. The arm 130 is provided with stepped shoulders 134, the arm 131 with stepped shoulders 135, and the arm 132 with stepped shoulders 136, and their positions with respect to the path of movement of the heel 129 is determined by the character of the operation being performed on the machine. In ordinary listing operations the lower shoulder 134 on the arm 130 will stop the movement of the designating character type carrier, with the result that no character is printed. However, a designating character, preferably a minus sign, is printed opposite a subtracted item as shown opposite the subtracted item "517 57" (Fig. 10).

A stud 137 on the arm 132 is held against a cam surface 138 on the lower side of the link 40 by a spring 139. A link 140 has its rear end pivoted to an extension of the stop arm 130 and its forward end guided by a stud 141. A projection 142 from the link 140 is engaged and moved forwardly by an extension 143 of the subtraction key lever 38 when said key lever is depressed. Upon depression of the subtraction key lever 38 the link 140 is moved forwardly a sufficient distance to lower the arm 130 entirely out of the path of movement of the heel 129. Since the link 40 is moved forwardly by depression of the subtraction key lever 38 the cam 138 moving away from the stud 137 permits the spring 139 to raise the arm 132 until the step 136 thereon is in the path of movement of the heel 129, as shown in Fig. 15. Then when the designating character type carrier moves forwardly it will advance until the heel 129 thereon engages the shoulder 136. This places the minus character type at the printing line so that upon operation of the printing mechanism in the usual way the minus sign will be printed opposite a subtracted item or opposite a negative total as an incident to the printing of such numbers.

A distinguishing character may also be printed to indicate positive totals. The shaft 39 upon which the total key lever 10 is mounted supports a depending arm 144. A plate 145 has a connection 146 with the arm 144 and a connection 147 with the link 140 and is guided by a stationary stud 148. When the total key 10 is operated it swings the arm 144 forwardly carrying with it the plate 145 and the link 140, thereby causing the arm 130 to move downwardly and permitting the heel 129 of the designating character type carrier to move forwardly over the arm 130 until it abuts against the shoulder 135 of the arm 131. In such position an asterisk or positive total character will be located at the printing line and printed with the printing of the positive total.

The invention may be varied in numerous respects without departure from the principle thereof. The mechanism for introducing an additional unit into units pinion 21 to obtain a correct negative total may be combined with various forms of adding and subtracting mechanisms, and there are many ways in which the invention may be embodied. In Figs. 16, 17, 18 and 19 (Sheet 1) one alternative form of the mechanism for controlling units counting pinion to obtain a correct negative total is shown, the device as there illustrated taking the place of the parts

67 to 70, inclusive, and the parts 72 to 94, inclusive. On the shaft 22 beyond the pinion 21 in the highest denominational order a special registering element or pinion 149 is mounted. A rack plate 150 similar to the rack plates 25 and similarly operated, and a pinion 151 similar to the pinions 19 and similarly operated are associated with the pinion 149 and controlled by the detent 26 in highest denominational order within the capacity of the machine. A pair of discs 152 and 153 are pinned to the pinion 149, each having a forward projection 154. The disc 153 has a notch 155 into which a stud 156 extends from the adjacent arm 23. The notch 155 is of sufficient length to permit movement of the disc 153 and the parts attached thereto to an extent equal to one tooth space of the pinion 149. A ball member 156 has one end integral with the disc 153 and the opposite end mounted on the shaft 22 in alignment with the latch 33 of units denominational order, and carries a cam 158 similar to one end of the cams 35 and cooperating with the cam portion 34 of the units latch 33 and operable in connection therewith to trip the detent 26 of units denominational order and permit the units rack 25 to operate as required to add or carry one into the units counting pinion 21. A blade 159 extending from the rear end of the total link 11 passes through a slot in the shaft 20 and is thereby guided in proper cooperative relationship with the projections 154 of the discs 152 and 153 and is effective to prevent setting of the clearing mechanism in a manner similar to the extensions 93 and 94 on the total link 11 until the machine has been given the proper number of operations 35 and until the subtraction key lever 38 is depressed for the printing of a negative total as previously explained.

As seen in Figs. 17 and 18, the projection 154 on the disc 152 is the analogue of the projection 40 93, and the projection 154 on the disc 153 is the analogue of the projection 94. The ball 157 is shifted laterally with the shaft 22 when said shaft is shifted laterally to align the pinions 21 with the racks 25 for direct adding operations or 45 with the pinions 19 for subtracting operations. Movement of the shaft 22 to align the pinions 21 with the pinions 19 locates the projection 154 that is on the disc 153 so that when said disc 153 is turned in a fugitive one transfer movement the 50 projection 154 on said disc 153 will prevent operation of the total key link 11, the same as the projection 94 prevents operation of the total key link 11, until the shaft 9 has been operated in one forward and back turning movement after 55 an item has been subtracted from another item represented in the pinions 21 and a negative total obtained; and the projection 154 on the disc 152 functions the same as the projection 93 on the total key link to prevent a clearing operation 60 of the machine until the shaft 9 has been operated forward and back after the character of the total has been changed from negative to positive.

A transfer movement is imparted to the special rack 150 corresponding to the special pinion 149 in precisely the same way as a transfer movement is imparted to the rack 25 that operates the pinion beyond highest denominational order in the machine already described. Such turning movement of the pinion 149 turns the discs 152 70 and 153 to place their respective projections 154 opposite the end of the blade 159 to block operation of the total key link 11 until the required additional forward and back turning movement of the shaft 9 has been performed to condition 75

the machine for a clearing operation. The stud 156 limits turning movements of the discs 152 and 153 to an extent sufficient for the cam 158 to trip the latch 33 in units denominational order 5 in introducing the fugitive one in any work requiring the introduction of the fugitive one into the units denominational pinion, and also stops the respective projections 154 in line with the blade 159.

10 According to the present invention, it is necessary to impart to the shaft 9 one forward and back turning movement in order to condition the machine for a clearing operation after any number 15 has been subtracted from any other number 15 represented in the counting pinions 21. The movements and adjustments of the arm 76 with respect to the arms 93 and 94 have been described and it is now clear that when any number 20 is represented in the counting pinions 21 and a smaller number is subtracted therefrom, a single forward and back turning movement of the shaft 9 is required while the key 38 remains unoperated in order to condition the machine for a clearing operation; and when any number is represented 25 in the counting pinions 21 and another number of larger numerical value is subtracted therefrom, it is necessary to operate the shaft 9 a single operation from and to its starting position while the subtracting key 38 is held depressed 30 in order to condition the machine for a clearing operation. When a positive number remains in the counting pinions 21 after an example of subtraction, a clearing operation must be performed while the subtraction key 38 remains unoperated; 35 and when a negative total is represented in the counting pinions 21, it is necessary to hold the subtraction key 38 depressed during the clearing operation.

40 In the important particular that only one forward and back turning movement of the shaft 9 is required in order to condition the machine for a clearing operation after the introduction of the subtrahend in any example of subtraction, this present invention is distinguished from the Dreher machine.

45 The invention is capable of wide variation and adaptation in other respects for use in different embodiments without departure from the principle of the invention. I do not restrict myself 50 in any unessential particulars, but what I claim and desire to secure by Letters Patent is:—

55 1. A calculating machine comprising calculating devices arranged in denominational orders, means controlled by the device in the highest denominational order to effect transfer into the units denominational order, mechanism operable from an unoperated to an operated position for controlling subtraction in said calculating devices, clearing mechanism, and means for preventing initiation of an operation of the clearing mechanism while said first named mechanism remains unoperated and while a negative total is 60 represented by said calculating devices.

65 2. A calculating machine comprising counting pinions arranged in denominational orders, actuators for operating said pinions, means for controlling transfer operation of said actuators, means controlled by the actuator of the highest denominational order controlling the transfer 70 operation of the actuator in units denominational order, mechanism operable from an unoperated to an operated position controlling subtraction in said counting pinions, clearing mechanism, and means for preventing initiation of an operation 75 of said clearing mechanism while said first named

mechanism remains in an unoperated position and said pinions represent a negative total.

3. A calculating machine comprising counting pinions arranged in denominational orders, actuators for operating said pinions, means for controlling transfer operation of said actuators, means controlled by the actuator in highest denominational order controlling the transfer operation of the actuator in said units denominational order, mechanism operable from an unoperated to an operated position controlling subtraction in said counting pinions, clearing mechanism, means for locking a part of said clearing mechanism while said first named mechanism remains unoperated and said pinions represent a negative total, and means for unlocking said part automatically and as an incident to change of the total represented by said pinions from negative to positive.

4. A calculating machine comprising calculating devices arranged in denominational orders, means controlled by the device in the highest denominational order controlling transfer of a unit into the units calculating device, a subtraction key, parts settable by said key to control the operation of said means, clearing mechanism, and an element settable by said means preventing initiation of an operation of said clearing mechanism while said subtraction key remains unoperated and said calculating devices represent a negative total.

5. In a calculating machine, total key connections, a lock shiftable to and from positions to prevent operation of said total key connections, a device for holding said lock in position to permit operation of said total key connections, means for operating said device to move said lock to position to prevent operation of said total key connections, a rock shaft, an element settable in operative and in inoperative positions, means for setting said element in operative position, connections operated by the rock shaft for operating said element, and means operated by said element for moving said device to position to permit operation of said device by said first named means.

6. In a calculating machine, a plurality of slides, a plate supported by each slide, an accumulator comprising a counting pinion for each plate, a pair of actuators associated with each plate for operating the corresponding pinion, an additional plate, means for imparting movement to said additional plate, a device controlling transfer movement of the plate in the units order, and means controlled by said additional plate for operating said device to cause a transfer movement of the plate in said units order.

7. In a calculating machine, a plurality of slides, a plate supported by each slide, an accumulator comprising a counting pinion for each plate, a pair of actuators associated with each plate for operating the corresponding pinion, an additional plate, means for imparting movement to said additional plate when said accumulator changes from positive to negative, a device controlling transfer movement of the plate in the units order, means controlled by said additional plate for operating said device to cause a transfer movement of the plate in said units order, total key connections, and means for preventing operation of said total key connections following transfer operation of the plate in said units order until said plate is returned to its starting position.

8. In a calculating machine, a plurality of

- slides, a plate supported by each slide, an accumulator comprising a counting pinion for each plate, a pair of actuators associated with each plate for operating the corresponding pinion, 5 an additional plate, means for imparting movement to said additional plate when said accumulator changes from positive to negative, a device controlling transfer movement of the plate in the units order, means controlled by said additional 10 plate for operating said device to cause a transfer movement of the plate in said units order, total key connections, means for preventing operation of said total key connections following transfer operation of the plate in said units order 15 when the total contained in said accumulator changes from positive to negative, mechanism having a forward and return stroke for operating said slides and thereby said actuators and said pinions in calculating and clearing operations, a 20 subtraction key, and devices controlled by said subtraction key and operative by a single forward and return stroke of said mechanism after the last number has been introduced into said accumulator for conditioning said means for a 25 clearing operation of said total key connections when said accumulator contains a negative total.
9. A calculating device comprising sliding plates arranged in denominational orders, a pair of actuators associated with each plate, an accumulator comprising a pinion for each plate to be operated by either actuator, a detent limiting sliding movement of each plate, a latch for each detent holding said detents in position to prevent 30 sliding movements of said plates, an additional plate controlled by the pinion of the highest order, and means controlled by said additional plate for releasing the latch of the detent controlling the plate in the units order to permit a transfer movement.
10. A calculating device comprising sliding plates arranged in denominational orders, a pair of actuators operated by each plate, an accumulator comprising a pinion for each plate to be 35 operated by either actuator, an additional plate controlled by the pinion of the highest order, a detent limiting sliding movement of each plate, a latch for each detent holding said detents in position to prevent sliding movements of said plates, means controlled by said additional plate for releasing the latch of the detent controlling the plate in the units order to permit a transfer movement, and means for restoring said detent and said latch in said units order to position 40 to prevent a transfer movement of the plate in said units order.
11. In a calculating machine, total key connections, an element mounted for sliding and turning movements, an arm supported by said element, means for moving said element to move said arm to position to permit or to prevent operation of said total key connections, calculating pinions arranged in denominational orders, a transfer device for the calculating pinion 45 in the units order, and means controlled by said element controlling transfer operation of said transfer device in said units order.
12. A calculating machine comprising counting pinions arranged in denominational orders, devices for operating said pinions in one direction for direct addition, devices for operating said pinions in the opposite direction for subtraction, 50 detents controlling transfer movement of said devices, latches for holding said detents in position to prevent transfer movement of said devices, means

operated by said pinions when said pinions are operated by either of said devices for releasing said latches, and means operative upon release of its latch by the pinion of the highest denominational order for releasing the latch of the units denominational order and thereby permitting the device aforesaid in said units denominational order to operate in its transferring movement.

13. A calculating machine comprising transfer devices, latches for holding said transfer devices from transfer operations, counting pinions operable to release said latches, a bail, a block member holding said bail in position to permit release of said latches, total key connections, means operated by said total key connections to move said block out of the way of said bail, and means controlled by the counting pinion of the highest denominational order for releasing the latch in the units order.

14. A machine of the character described comprising a plurality of sliding actuator plates, counting pinions, means for operating said counting pinions by said plates, detents for stopping movement of said plates in each of two positions, means for moving said detents from one position to another position, a bail for restoring said detents to the first position, latches for holding said detents in said first position, and means controlled by the counting pinion of the highest denominational order for releasing the latch of the units order and for causing the pinion in the units order to move a distance representing one unit.

15. The combination in a calculating machine of a plurality of actuators arranged in denominational orders, a plurality of registering elements identified with the actuators and operable thereby to accumulate numbers either additively or subtractively and to represent the true algebraic sum thereof notwithstanding the said sum may alternately be of a positive or a negative character, means controlled by the registering element of the highest order for moving the registering element in the lowest denominational order a distance corresponding to one unit as an incident to a change in the character of the sum represented by said registering elements, devices for causing said actuators to operate said registering elements to the initial positions of said registering elements, means for conditioning said registering elements for operation of said devices, and means for preventing operation of said devices until said registering elements have been conditioned for such operation of said devices.

16. The combination in a calculating machine of two series of actuators arranged in denominational orders, a plurality of registering elements identified with the two series of actuators and operable optionally thereby to accumulate numbers additively or subtractively and to represent the true algebraic sum thereof notwithstanding the said sum may alternately be of a positive or a negative character, automatic means controlled by the registering element of the highest order whereby the actuator in the lowest denominational order will be caused to move the said identified registering element a distance corresponding to one unit as an incident to a change in the character of the sum represented by said registering elements, and recording means for operating said actuators and recording the numbers as an incident to the accumulation thereof.

17. The combination in a calculating machine

of a plurality of actuators arranged in denominational orders, a plurality of registering elements having a positive zero position and a negative zero position, said registering elements being identified with the actuators and operable thereby to accumulate numbers either additively or subtractively and to represent the true algebraic sum thereof notwithstanding the said sum may alternately be of a positive or a negative character, automatic means controlled by the registering element of the highest order whereby the actuator in the lowest denominational order will be caused to move the registering element in the units order a distance corresponding to one unit as an incident to a change in the character of the sum represented by said registering elements, and clearing means whereby said registering elements may be set in either of their zero positions.

18. The combination in a calculating machine of a plurality of actuators arranged in denominational orders, a plurality of registering elements having a positive zero position and a negative zero position, said registering elements being identified with the actuators and operable thereby to accumulate numbers either additively or subtractively and to represent the true algebraic sum thereof notwithstanding the said sum may alternately be of a positive or a negative character, automatic means controlled by the registering element of the highest order whereby the registering element in the lowest denominational order will be caused to move a distance corresponding to one unit as an incident to a change in the character of the sum represented by said registering elements, clearing means whereby said registering elements may be set in either of their zero positions, and recording means operable to print the sum represented by the registering elements as an incident to the setting of said elements in zero position.

19. The combination in a calculating machine of a series of actuators arranged in denominational orders, a series of registering elements having a positive zero position and a negative zero position, said registering elements being identified with the actuators and operable thereby to accumulate numbers either additively or subtractively and to represent the true algebraic sum thereof notwithstanding the said sum may alternately be of a positive or a negative character, automatic means controlled by the registering element of the highest order whereby the registering element in lowest denominational order will be caused to move a distance corresponding to one unit as an incident to a change in the character of the sum represented by said registering elements, clearing means whereby said registering elements may be set in either of their zero positions, and locking means preventing the setting of said registering elements in a clear position other than the proper clear position of the sum then represented thereby.

20. In a calculating machine, a series of rack members arranged side by side in denominational orders, a series of pinions also in said denominational orders and each thereof being actuated by a corresponding rack member, a tripping member mounted on each of said pinions, and a series of latch members corresponding to said tripping members and adapted to be tripped thereby, each latch when tripped being operable to permit movement of the rack member in the next higher denominational order, in combination with an oscillating member, a special tripping member cooperating with said oscillating member and

operable as an incident to the movement thereof to trip the latch member of the lowest denominational order, and an element controlled by the pinion of the highest order for moving said oscillating member.

21. The combination in a calculating machine having a series of trains of mechanism arranged in denominational orders, each train including a rack member, a pinion, a tripping member operated by the pinion, and a latch member; of an oscillating member having a positive position and a negative position; an element controlled by the pinion of the highest order for moving said oscillating member from one of its positions to the other; and a special tripping member co-operating with said oscillating member and operable as an incident to the movement thereof to trip the latch member of the lowest denominational order.

22. The combination in a calculating machine, of a revoluble registering element identified with each of a plurality of denominational orders, each of said elements having a positive clear position and, separated therefrom by the distance corresponding to one unit, a negative clear position, spring-actuated means controlled by the registering element in the highest denominational order as an incident to every movement of said registering element from its positive clear position to its negative clear position through the said space of one unit, whereby the element in the units order will be caused to register the subtraction of one unit, and printing mechanism operable under control of said registering elements to print simultaneously the entire total represented by any number of said registering elements.

23. The combination in a calculating machine, of a revoluble registering element identified with each of a plurality of denominational orders, each of said elements having a positive clear position from which it advances to register addition and a negative clear position, the said negative clear position and the said positive clear position being separated by the space corresponding to one unit, spring-actuated means associated with the element in the highest denominational order whereby the element in the units order will be caused to register the subtraction of one unit as an incident to every initial movement beyond said positive clear position in the direction for registering subtraction of said element in the highest denominational order, and printing mechanism operable under control of said registering elements to print simultaneously the entire total represented by any number of said registering elements.

24. The combination in a calculating machine, of a series of registering pinions arranged in denominational orders, a series of actuators operable to turn the pinions in one direction for addition and in the opposite direction for subtraction, mechanism for controlling operation of said actuators to effect transferring of tens from the lower to the higher orders as required in addition and in subtraction, a special registering element having a positive position and a negative position, means operable to move said element from one position to the other according to the character of any amount represented by said registering pinions whether positive or negative, and means under control of said special element whereby the registering pinion of the lowest denominational order will be caused to move the distance of one unit as an incident to every movement of said element.

25. The combination in a calculating machine, of a series of registering elements having clear position before being operated to accumulate numbers, one thereof being identified with each 5 of a plurality of denominational orders, differential actuators one for each of said registering elements, said registering elements being normally arranged to accumulate numbers additively, manipulative means controlling adjustment of said registering elements for subtraction, automatic spring-actuated means controlled by the registering element in the highest order whereby the registering element in the units order will be caused to move a distance corresponding to 10 one unit as an incident to every change of the amount represented by said registering elements from positive to negative or from negative to positive, and clearing mechanism operable at a single 15 operation to set all of said registering elements in clear position.
26. The combination in a calculating machine having a series of trains of mechanisms arranged in denominational orders, each train including a rack member, a pinion having a positive 20 zero position and a negative zero position, a tripping member operated by the pinion, and a latch member; of an oscillating member having a positive position and a negative position; an element controlled by the train of mechanism of 25 the highest order for moving said oscillating member from one of its positions to the other; a special tripping member cooperating with said oscillating member and operable as an incident to the movement thereof to trip the latch member 30 of the lowest denominational order; clearing means whereby the said pinions may be set in either of their zero positions; a total key device controlling operation of said clearing means when said pinions represent a positive total; and an 35 abutment carried by the oscillating member and operable to engage a part of the said total key device and thereby prevent initiation of a clearing 40 operation while said subtraction key device remains unoperated and said pinions represent a negative total.
27. The combination in a calculating machine having a series of trains of mechanisms arranged in denominational orders, each train including a rack member, a pinion having a positive zero 45 position and a negative zero position, a tripping member operated by the pinion, and a latch member; of an oscillating member having a positive position and a negative position; an element controlled by the train of mechanism of 50 the highest order for moving said oscillating member from one of its positions to the other; a special tripping member cooperating with said oscillating member and operable as an incident to the movement thereof to trip the latch member 55 of the lowest denominational order; clearing means whereby the said pinions may be set in either of their zero positions; a total key device controlling operation of said clearing means when said pinions represent a positive total; an abutment 60 carried by the oscillating member and operable to engage a part of said total key device and thereby prevent the setting of said pinions in a clear position of a character other than that of the sum then represented thereby; and means 65 for disabling the connection between said abutment and the clearing means.
28. A calculating machine operative in calculating and clearing operations and comprising calculating devices arranged in denominational 70 orders, mechanism operable from an unoperated

to an operated position to shift said calculating devices from one position to another, means controlled by the calculating device of the highest denominational order controlling transfer of a unit into the units calculating device, and an element preventing a clearing operation of the machine while said mechanism remains in an unoperated position and the calculating devices represent a negative total.

29. A calculating machine operative in calculating and clearing operations and comprising counting pinions arranged in denominational orders, mechanism for operating said pinions in calculating and transfer operations in one direction for addition and in the reverse direction 10 for subtraction, connections for shifting said pinions from position for addition operation to position for subtraction operation, a transfer device for the units pinion controlled by the reverse direction operation of the pinion in the highest 15 denominational order to introduce a negative unit in said units pinion, and means preventing a clearing operation of the machine while said connections remain unoperated when a negative 20 total is represented by said pinions.

30. The combination in a calculating machine of depressible keys, differential mechanism controlled by said keys, a series of actuators controlled by said differential mechanism and arranged in denominational orders, a series of pinions operated by said actuators to accumulate numbers either additively or subtractively, a series of recording devices operable under control of the said pinions to print the true algebraic sums of the numbers accumulated whether said sums 35 be positive or negative, and means controlled by the pinion of the highest order whereby said sums to be printed will be rectified to the extent of one unit before operation of said recording devices to print said sums and as an incident to 40 a change in the character of the sum of the numbers accumulated by the said pinions from positive to negative.

31. The combination in a calculating machine of depressible keys, a series of actuators controlled by the keys and arranged in denominational orders, a series of registering elements operated by said actuators to accumulate numbers either additively or subtractively, a series of recording devices identified with and operated under control of the registering elements to print the true algebraic total of the numbers accumulated by said registering elements whether said total be of a positive or a negative character, automatic means controlled by the registering elements of the highest order whereby a total to be printed will be rectified to the extent of one unit concurrently with and as an incident to a change from positive to negative of the total of the numbers accumulated, and means whereby said registering elements may be set in a clear position for operation to accumulate a positive total as an incident to a total printing operation.

32. In a machine for adding, subtracting and recording numbers and printing the algebraic totals thereof, the combination of a series of registering pinions arranged in denominational orders, a series of actuators for turning the pinions in addition and in subtraction, a series of printing devices identified with the pinions and 60 operable under control thereof to print totals, mechanism for transferring from lower to higher order as required in addition and in subtraction, a special registering element having a positive position and a negative position, means operable to 75

move said special registering element from one position to the other according to the character of an amount represented by said registering pinions whether positive or negative, and means under control of said special registering element whereby the potential amount of a total to be printed by said printing devices will be rectified to the extent of one unit as an incident to the movement of said special registering element and before operation of said printing devices to print said total.

33. A calculating machine comprising counting pinions arranged in denominational orders, devices for operating said pinions in one direction for addition, devices for operating said pinions in the opposite direction for subtraction, abutment members controlling transfer movements of said devices, latches for holding said abutment members in position to prevent transfer movement of said devices, means operated by each of said pinions when said pinions are operated by either of said sets of devices for releasing a latch when transfer is to be made from a pinion, and means operative upon release of a latch by the pinion of the highest denominational order for releasing an abutment member of the units denominational order and thereby permitting one of the devices aforesaid to operate the units pinion to the extent of one unit.

34. A calculating and recording machine comprising counting pinions arranged in denominational orders, a series of devices for operating said pinions in one direction for addition, a series of devices for operating said pinions in the opposite direction for subtraction, differential mechanism controlling both of said series of devices, abutment members controlling transfer movements of both series of said devices, latches for holding said abutment members in position to prevent transfer movement of said devices, means operated by each of said pinions when said pinions are operated by either of said series of devices for releasing a latch, and means operative upon release of a latch by the pinion of the highest denominational order for releasing an abutment member of the units denominational order and thereby permitting one of the devices aforesaid to operate the units pinion to the extent of one unit.

35. A calculating machine comprising counting pinions arranged in denominational orders, a series of devices for operating said pinions in one direction for addition, a series of devices for operating said pinions in the opposite direction for subtraction, abutment members controlling transfer movements of both series of said devices, latches for holding said abutment members in position to prevent transfer movement of said devices, means operated by each of said pinions when said pinions are operated by either of said series of devices for releasing a latch, means operative upon release of a latch by the pinion of the highest denominational order for releasing an abutment member of the units denominational order and thereby permitting one of the devices aforesaid to operate the units pinion to the extent of one unit, and clearing means whereby the said pinions may be set in clear position through either series of said devices.

36. A calculating and recording machine comprising counting pinions arranged in denominational orders, a series of devices for operating said pinions in one direction for addition, a series of devices for operating said pinions in the opposite direction for subtraction, differential

mechanism for controlling both sets of said devices, abutment members controlling transfer movements of both series of said devices, latches for holding said abutment members in position to prevent transfer movement of said devices, means operated by each of said pinions when said pinions are operated by either of said series of devices for releasing a latch, means operative upon release of a latch by the pinion of the highest denominational order for releasing an abutment member of the units denominational order and thereby permitting one of the devices aforesaid to operate the units pinion to the extent of one unit, and recording devices operable to record the numbers introduced by the keys as an incident to the addition or subtraction thereof.

37. A calculating and recording machine comprising a series of counting pinions, separate sets of actuators for operating said pinions to obtain positive totals in addition and negative totals in subtraction, a series of recording devices operable under control of the actuators to print the totals represented on said counting pinions, clearing mechanism, means signifying the presence of a negative total and preventing initiation of an operation of said clearing mechanism when a negative total is represented by said pinions, mechanism for rendering said means ineffective, a subtraction key controlling said last named mechanism, a rock shaft movable from and to a definite starting position, and parts operated by said rock shaft for operating said last named mechanism to render said means ineffective to prevent initiation of an operation of said clearing mechanism by a single operation of said rock shaft from and to said starting position following an operation to obtain a negative total in said counting pinions.

38. The combination in a calculating machine of depressible keys, two series of actuators controlled by the keys and arranged in denominational orders, a series of registering elements identified with the two series of actuators and operable optionally thereby to accumulate numbers positively or subtractively and to represent the true algebraic sum thereof notwithstanding the said sum may alternately be of a positive or negative character, automatic means controlled by the registering element of the highest order whereby the actuators in the lowest denominational order will be caused to move the said identified element a distance corresponding to one unit as an incident to a change in the character of the sum represented by said registering elements, and mechanism controlling setting of said registering elements in zero position by one of said series of actuators when a negative total is contained in said registering elements.

39. The combination in a calculating machine of depressible keys, two series of actuators controlled by the keys and arranged in denominational orders, a series of registering elements having a positive zero position and a negative zero position, said registering elements being identified with the two series of actuators and operable optionally thereby to accumulate numbers either additively or subtractively and to represent the true algebraic sum thereof notwithstanding the said sum may alternately be of a positive or negative character, automatic means whereby the actuators in the lowest denominational order will be caused to move the identified registering element a distance corresponding to one unit as an incident to a change in the character of the

sum represented by said registering elements, clearing means whereby said elements may be set in either of their zero positions, and recording means operable to print the sum represented by the registering elements as an incident to the setting of said elements in zero position.

40. The combination in a calculating machine of depressible keys, two series of actuators controlled by the keys and arranged in denominational orders, a series of registering elements having a positive zero position and a negative zero position, said registering elements being identified with the two series of actuators and operable optionally thereby to accumulate numbers either 10 additively or subtractively and to represent the true algebraic sum thereof notwithstanding the said sum may alternately be of a positive or a negative character, automatic means controlled by the registering element of the highest order 15 whereby the actuators in the lowest denominational order will be caused to move the identified registered element a distance corresponding to one unit as an incident to a change in the character of the sum represented by said registering 20 elements, clearing means whereby said registering elements may be set in either of their zero positions, and locking means preventing the setting of said registering elements in a clear position other than the proper clear position of the 25 sum then represented thereby.

41. In a calculating and recording machine having a series of trains of mechanism arranged in denominational orders and operable to add and subtract numbers and to print a list thereof together with the algebraic total, an oscillating member, a tripping member, a latch member, an abutment member, and a rack member, certain of said members being identified with the units denominational order and the remainder thereof 30 with the highest denominational order, in combination with an element controlled by a part of said mechanism in said highest order for moving the said oscillating member and thereby through the said tripping member, latch member and abutment member, permitting movement of 35 said rack member.

42. The combination in a calculating and recording machine operable to add, subtract and record numbers and to print the algebraic totals thereof and having a series of trains of mechanisms arranged in denominational orders, each of said trains including a spring driven rack member, a pinion, a tripping member operated by the pinion, and an abutment member; of an oscillating member having a positive and a negative position; an element controlled by the pinion of the highest order for moving said oscillating member from one of its positions to the other; and a special tripping member cooperating with said oscillating member and operable as an incident to the movement thereof to release the abutment member in the lowest denominational order and thereby permit its rack member to move in a transfer operation.

43. The combination in a calculating and recording machine operable to add, subtract and record numbers and to print the algebraic totals thereof and having a series of trains of mechanism arranged in denominational orders, each of said trains including a yieldingly actuated rack member, a pinion, a tripping member operated by the pinion, a latch member, and an abutment member; of an oscillating member having a positive and a negative position; an element controlled by the pinion of the highest

order for moving said oscillating member from one of its positions to the other; and a special tripping member cooperating with said oscillating member and operable as an incident to the movement thereof to trip the latch member of the lowest denominational order. 5

44. In a calculating and recording machine for adding, subtracting and recording numbers and printing the algebraic totals thereof, the combination with total printing mechanism and manipulative means for controlling operation thereof, of a series of revolute registering elements identified with each of a plurality of denominational orders, each of said elements having a positive clear position and separated therefrom by 10 the distance corresponding to one unit, a negative clear position, and means controlled by the registering element in the highest denominational order as an incident to the movement of said registering element from its positive clear 15 position to its negative clear position through the said space of one unit whereby the element in the units order will be caused to register the subtraction of one unit and operation of said manipulative means will be blocked. 20

45. In a calculating and recording machine for adding, subtracting and recording numbers and printing the algebraic totals thereof, the combination with total printing mechanism and manipulative means for controlling operation 30 thereof, operable to print simultaneously a plurality of digits, of revolute registering elements identified with each of a plurality of denominational orders, each of said elements having a positive clear position from which it advances 35 to register addition and a negative clear position, the said negative clear position and the said positive clear position being separated by the space corresponding to one unit, and spring-actuated means controlled by the element in the 40 highest denominational order whereby the element in the units order will be caused to register the subtraction of one unit and operation of said manipulative means will be blocked as an incident to every initial movement beyond said 45 positive clear position in the direction for registering subtraction of said element in highest denominational order.

46. In a calculating and recording machine for adding, subtracting and recording numbers 50 and printing the algebraic totals thereof, the combination with total printing mechanism and manipulative means for controlling operation thereof of a series of registering pinions arranged in denominational orders, a series of spring driven actuators operable to turn the pinions in one direction for addition and in the opposite direction for subtraction, mechanism for transferring of tens from a lower to a higher order as required in addition and in subtraction, an element having a positive position and a negative position, means controlled by the pinion of the highest order to move said element from one position to the other when the character of an amount represented by said registering pinions 60 changes from or to positive or negative, and means under control of said element whereby the actuator of the lowest denominational order will be caused to move the pinion of the lowest order the distance of one unit and operation of said 70 manipulative means will be blocked as an incident to a movement of said element to said negative position.

47. In a calculating and recording machine for adding, subtracting and recording numbers 75

and printing the algebraic totals thereof, the combination with total printing mechanism and manipulative means controlling operation thereof, of a series of registering elements, one thereof being identified with each of a plurality of denominational orders, said registering elements being normally arranged to accumulate numbers positively, means whereby said registering elements may be adjusted for the accumulation of numbers subtractively, and automatic means controlled by the registering element of the highest order whereby the registering element in the units order will be caused to move a distance corresponding to one unit and operation of said manipulative means will be blocked as an incident to the change of the amount represented by said registering elements from positive to negative.

48. A calculating machine comprising two sets of actuators arranged in laterally spaced relationship in which the actuators of each set alternate with the actuators of the other set, a number of laterally shiftable calculating pinions arranged in denominational orders and rotatable by one of said sets of actuators in one lateral position of said pinions and rotatable by the other set of actuators in another lateral position of said pinions, means for engaging said pinions with one of said sets of actuators in one of the lateral positions of said pinions, and with the other set of actuators in the other lateral position of said pinions, a transfer device for each of said pinions, and means controlled by the pinion of the highest order for causing the transfer device for said units pinion to operate.

49. A calculating machine comprising a plurality of laterally shiftable counting pinions arranged in denominational orders and rotatable in either of two lateral positions, separate sets of laterally aligned actuators for operating said pinions in the different lateral positions of said pinions to obtain positive totals in addition in one lateral position of said pinions and negative totals in subtraction in another lateral position of said pinions, clearing mechanism, a rock shaft movable to and from a definite starting position, a device for preventing initiation of an operation of said clearing mechanism and signifying the presence of a negative total, a subtraction key, mechanism controlled by said subtraction key, and means for operating said mechanism by said rock shaft to move said device to position to permit initiation of an operation of said clearing mechanism.

50. A calculating machine comprising a plurality of axially aligned laterally shiftable calculating pinions arranged in denominational orders and rotatable in one lateral position to obtain positive totals in addition, and rotatable in another lateral position to obtain negative totals in subtraction, separate sets of actuators for operating said pinions to obtain positive totals in addition and negative totals in subtraction in the respective lateral positions of said pinions, clearing mechanism, a device for preventing initiation of an operation of said clearing mechanism and signifying the presence of a negative total in said pinions, a rock shaft movable from and to a definite starting position, a subtraction key, means controlled by a single operation of said rock shaft to and from starting position controlled by said key and operated by said rock shaft for positioning said device to permit initiation of an operation of said clearing mechanism in clearing said negative total.

51. A calculating machine comprising a number of laterally shiftable calculating pinions arranged in denominational orders and rotatable in either of two lateral positions, two sets of elements for rotating said pinions in said positions, means for engaging said pinions with one of said sets of elements in one of the lateral positions of said pinions and with the other set of said elements in the other lateral position of said pinions, a device controlled by said pinion of the highest order for controlling transfer operation of one of said elements for the units pinion, clearing mechanism for clearing said pinions, a rock shaft movable from and to a definite starting position, a subtraction key, and mechanism controlled by said subtraction key and operated by said rock shaft for conditioning said clearing mechanism for cooperation with said calculating pinions by a single movement of said rock shaft from and to said definite starting position after the last number has been introduced into said pinions when said pinions contain a negative total and irrespective of which set of said elements had rotated said pinions.

52. A calculating machine comprising a number of laterally shiftable calculating pinions arranged in denominational orders and rotatable in either of two lateral positions, two sets of elements for rotating said pinions in said positions, means for engaging said pinions with one of said sets of elements in one of the lateral positions of said pinions and with the other set of said elements in the other lateral position of said pinions, a device for controlling an entry of a fugitive one in the units pinion by the element of either set in units order, and means controlled by the calculating pinion of the highest denominational order for controlling the fugitive one entry by said elements.

53. A calculating and recording machine comprising two sets of actuators, counting pinions arranged in denominational orders for operation in each of two lateral positions, mechanism for engaging said pinions with said respective sets of actuators in the respective lateral positions of said pinions, recording devices controlled by the engaged set of actuators for recording the totals of the numbers introduced into said pinions, clearing mechanism for effecting control of said recording mechanism by said actuators, and means controlled by the counting pinion in the highest denominational order for causing one of the actuators for the units pinion to introduce the fugitive one when the total changes from positive to negative and for causing the other actuator for the units pinion to introduce the fugitive one when the total changes from negative to positive.

54. A calculating machine comprising separate sets of actuators, a series of slides for operating said actuators, latches controlling movement of said slides relative to said actuators, a set of calculating pinions, key connections controlling shifting of said calculating pinions from one set of actuators to the other, means for operating one set of actuators to transfer from the lower to the higher denominational orders in said calculating pinions when said calculating pinions engage said set of actuators, and for operating the other set of actuators to transfer when said calculating pinions engage said other set of actuators, and mechanism controlled by the calculating pinion in the highest denominational order for causing the respective actuators for the units pinion to introduce the fugitive one

into the units pinion when the total in said pinions changes from positive to negative or from negative to positive.

55. A calculating machine comprising elements operative on a forward and a return stroke, a series of plates arranged in denominational orders operated by said elements, means for supporting said plates for sliding movement relative to said elements, two sets of racks rigid with said plates, a shaft extending transversely between the two sets of racks, a series of pinions rotative on said shaft and meshing with one set of said racks and having their peripheries in alinement with the other set of racks, a series of calculating pinions engageable optionally with said other set of racks or with said pinions, and mechanism controlled by the calculating pinion in the highest denominational order for introducing the fugitive one into the calculating pinion in the units denominational order to obtain a correct negative total.

56. Computing mechanism comprising a set of racks, a set of pinions arranged to be rotated by the racks, a spring tending to move the units rack to introduce the fugitive unit, a pawl to restrain the units rack, transfer devices for the remaining racks, a lug connected to revolve with the pinion of the highest order, and means arranged to be engaged by said lug and connected to said pawl to move the latter out of the units-rack-restraining position.

57. Computing mechanism comprising a set of racks, a set of pinions arranged to be rotated by the racks, a spring tending to move the units rack to introduce the fugitive unit, a pawl to restrain the units rack, transfer devices for the remaining racks, a lug connected to revolve with the pinion of the highest order, and a spring-actuated member arranged to be tripped by said lug, said spring-actuated member being connected to said pawl to move the latter out of the units-rack-restraining position when said spring-actuated member is tripped by said lug.

58. A totalizer comprising a set of pinions arranged to be rotated in one direction to add and in the opposite direction to subtract, means to turn the units pinion in one direction to introduce the fugitive unit, means to turn the units pinion in the opposite direction to introduce the fugitive unit, each of said pinions having twenty teeth, two diametrically opposite lugs arranged to revolve with the pinion of the highest order, and means arranged to be actuated by said lugs to control the fugitive-unit-introducing means.

59. A calculating and recording machine comprising a series of calculating pinions arranged in denominational orders and rotative in either of two positions, two series of elements for rotating said pinions in said two positions to introduce numbers into said pinions, mechanism having a forward and return stroke for operating said elements and thereby said pinions in calculating and clearing operations, a device for controlling transfer operation of one of said elements for the units pinion, means for conditioning said pinions for a positive clearing operation by a single forward and return stroke of said mechanism after the last number has been introduced into said pinions, and means for controlling said pinions for a negative clearing operation by a single forward and return stroke of said mechanism after the last number has been introduced into said pinions.

60. A calculating machine comprising a number of shiftable calculating pinions arranged in

denominational orders and rotatable in either of two positions, two sets of elements for rotating said pinions in said positions, a device controlled by the pinion of the highest order for controlling transfer operation of one of said elements for the units pinion to introduce the fugitive one in subtraction, mechanism having a forward and return stroke for operating said elements and thereby said pinions in calculating and clearing operations, means for conditioning said pinions for a negative clearing operation by a single forward and return stroke of said mechanism after the last number has been introduced into said pinions and a negative total is represented in said pinions, and devices cooperative with said pinions and a means for maintaining a cooperative relationship between said mechanism and said elements and said pinions during a clearing operation. 5

61. A calculating machine comprising a number of shiftable calculating pinions arranged in denominational orders and being rotative in either of two positions in complete calculating operations including transferring and clearing operations, two series of elements for engaging and rotating said pinions in said two positions in said complete calculating operations, and means controlled by the pinion of the highest denominational order for controlling the transfer operation of said elements for the units pinion to introduce the fugitive one into said units pinion as an incident to a change in the character of the sum represented by said pinions.

62. A calculating machine comprising a number of shiftable calculating pinions mounted in denominational orders and being rotative in either of two positions in complete calculating operations including transferring and clearing operations, an element for engaging and rotating each of said pinions in one of said positions, another element for engaging and rotating each of 40 said pinions in the other of said two positions, and means controlled by the pinion of the highest denominational order for controlling the transfer operation of said two elements for the units pinion to introduce the fugitive one into 45 said units pinion as an incident to a change from positive to negative, or vice versa, in the character of the sum represented by said pinions.

63. A calculating machine comprising a number of shiftable calculating pinions arranged in denominational orders and being rotative in either of two positions in complete calculating operations including transferring and clearing operations, two series of elements for engaging and rotating said pinions in said two positions in said complete calculating operations, means controlled by the pinion of the highest denominational order for controlling the transfer operation of said elements for the units pinion to introduce the fugitive one into said units pinion 60 as an incident to a change in the character of the sum represented by said pinions, mechanism having a forward and return stroke for operating said elements, and thereby said pinions, in calculating and clearing operations, and devices 65 operated by a part of said mechanism during a single forward and return stroke thereof for conditioning said elements to operate said pinions in a clearing operation after the last number has been introduced into said pinions in any of the 70 calculating operations of said pinions.

64. A calculating machine comprising a number of shiftable calculating pinions mounted in denominational orders and being rotative in either of two positions in complete calculating 75

- operations including transferring and clearing operations, an element for engaging and rotating each of said pinions in one of said positions, another element for engaging and rotating each of said pinions in the other of said two positions, means controlled by the pinion of the highest denominational order for controlling the transfer operation of said two elements for the units pinion to introduce the fugitive one into said 10 units pinion as an incident to a change from positive to negative, or vice versa, in the character of the sum represented by said pinions, mechanism having a forward and return stroke for operating said elements, and thereby said pinions, 15 in calculating and clearing operations, and devices operated by a part of said mechanism during a single forward and return stroke thereof for conditioning said elements to operate said pinions in a clearing operation after the last 20 number has been introduced into said pinions in any of the calculating operations of said pinions.
65. A calculating machine comprising calculat-
- ing pinions in denominational orders, a set of actuators for operating said pinions in addition, another set of actuators for operating said pinions in subtraction, a subtraction key, devices controlled by said subtraction key for controlling operation of said pinions by said second set of actuators, mechanism for operating said devices and thereby controlling subtraction in said calculating pinions, clearing mechanism, means settable by the calculating pinion in the highest 10 denominational order for preventing initiation of an operation of said clearing mechanism after operation of said pinions by said second set of actuators when a negative total is represented by said pinions, and elements controlled by said 15 subtraction key and operated by a part of said mechanism for conditioning the machine for a clearing operation by a single operation of said mechanism after the last number has been introduced into said pinions and a negative total 20 is represented thereby.

BIRNEY DYSART.
